UNITED STATES PATENT OFFICE.

GEORGE J. MURDOCK, OF NEW YORK, N. Y.

SAD-IRON.

SPECIFICATION forming part of Letters Patent No. 379,804, dated March 20, 1888.

Application filed February 7, 1887. Serial No. 226,769. (No model.)

To all whom it may concern:

Be it known that I, GEORGE J. MURDOCK, of the city and State of New York, have invented an Improvement in Sad-Irons, of which 5 the following is a specification.

This invention is an improvement upon that set forth in the patent, No. 356,881, granted February 1, 1887, to G. J. Murdock and J. P. Murdock. In this patent a bell is provided

10 with an external arm and hammer that is rung by the action of a thermostat; but the arm of the hammer is liable to be injured by heat and to be broken in the rough usage to which sad-irons are often exposed. In my present im- 15 provements the hammer is within the bell and protected by it, and there is a separate visual- signal that indicates when the hammer is set, and also shows when the bell has been rung, and this hammer is self-acting, and it swings 20 into position by the ordinary movement of the sad-iron while being used, so as to be set when the iron is placed on the fire, and this hammer is unlatched by the action of the heat and causes the clapper to strike the bell; and the 25 removable shank of the wooden handle is pro- vided with a catch that prevents the handle from accidentally becoming disconnected while in use.

In the drawings, Figure 1 is a vertical sec- 30 tion at the line $x-x$, Fig. 2, showing my im- provements. Fig. 2 is a plan view with the bell removed and the stock of the handle in section at the line $y-y$, and Fig. 3 is a front ele- vation of the hammer and latch. Fig. 4 is a 35 section at $x-x$ through the handle, and Fig. 5 is a section at $y-y$.

The sad-iron a is of any desired size and shape, and upon the front part of this rises the stock l , having a head, m , that is provided 40 with a slightly-tapering hole for the reception of the metal shank 6 of the wooden handle n , and around the shank 6 is a conical collar, 7 , having several notches in it, preferably four. Upon the top of the head m is a pivot, 21 , and 45 a latch, 22 , having an enlarged head, 20 , as seen in Figs. 4 and 5, so that when the shank 6 has been inserted into the opening in the head m the latch 22 catches into one of the notches in the conical collar, and the head 20 50 holds the collar so that the handle will not be-

come detached accidentally; but when the latch 22 is raised by the thumb or finger placed under the projecting end or arm of said latch the handle can be drawn back and removed.

The stock l is preferably nearly a quarter- 55 sphere and hollow, so that the bell B is par- tially received within the same, and it is sus- pended from the stock by a screw passing through the tongue or strap 23 .

The thermostat H is of any desired character. 60 It is preferably of two dissimilar strips of metal riveted together and secured to the top of the sad-iron by the screws 2 , and the ex- pansion under the action of the heat causes the loose end of the thermostat, which is be- 65 neath the bell, to rise up; and there is a mortise through the stock l , that allows for the pas- sage of the thermostat; and at the end of the thermostat and below the bell there is a latch, 70 E , pivoted at 24 , and provided with an adjust- ing-screw, 25 , by which the point of the latch can be raised or lowered.

The hammer F is pivoted at 26 , at its lower end, preferably to the removable base D , 75 which is attached by the screw W in a recess formed in the front part of the sad-iron. Pro- jecting from this hammer F is the visual-sig- 80 nals V , and there is a suitable stop, U , behind the hammer to prevent it swinging too far to- 85 ward the end of the thermostat. This visual- signal V is in the form of a wire within a ver- tical slot at the front part of the sad-iron, and it limits the fall of the hammer, and also in- 90 dicates which bell has been rung when there are a number of sad-irons on the stove. It 95 will now be understood that the thermostat has only to carry the weight of the latch E , and hence said thermostat responds freely to differences in the temperature, and that the hammer F is held back by the latch E as soon as the iron cools sufficiently for the latch E to descend, because as the iron is rubbed back and forth upon the fabric the hammer F will 100 swing upon its pivot until the latch E de- scends and holds the hammer, and in this po- sition the signal V will be raised to indicate that the hammer is properly set. When the thermostat is sufficiently warm to unlatch the hammer F , it falls forward by its own weight, aided by the leverage of the signal V ; and the 105

bell may be struck by the hammer itself or by any suitable clapper. I prefer to make use of the clapper G, pivoted at 30 to the plate D, and having a head that will strike the rim of

5 the bell; and there is a projection, J, upon the hammer F, that strikes the clapper to swing the same and ring the bell.

The lower end of the clapper G is preferably slotted for the signal V to pass through freely, 10 and the upper end of the hammer F is by preference forked, so that the latch E is between the two sides of the fork.

The parts of the alarm apparatus are strong and not liable to injury, and whenever the 15 heat of the iron reaches such a point that the thermostat unlatches the hammer F it falls and the alarm is given by ringing the bell. The hammer F occupying almost a perpendicular position, the weight thereof rests upon 20 the pivot 26, and there is very little friction between the end of the latch E and the hammer F; hence there is but little resistance to the movement of the thermostat and the latch; and when the iron has been used a short time 25 the end of the latch E will catch the hammer F as it is thrown into the path of the latch by the swinging movement aforesaid, and the thermostat is free to resume its normal state.

I claim as my invention—

30 1. The combination, with the sad-iron and the thermostat thereon, of a latch, a pivot to connect the latch to the thermostat, a screw to

adjust the latch, a hammer held by the latch and liberated by the thermostat, and a bell to be rung by the hammer, substantially as set 35 forth.

2. The combination, with the sad-iron and its stock, of a bell fastened at the upper part to the stock, a thermostat attached to the upper surface of the iron, a latch upon the thermostat, a pivoted hammer below and within the bell and held by the latch, and a visual-signal connected with the hammer and extending outside the bell, so as to indicate whether such hammer is held by the latch or 45 not, substantially as set forth.

3. The combination, with the sad-iron, the thermostat, and the bell, of a latch connected with the thermostat, a pivoted hammer, and a pivoted clapper, against which the hammer 50 acts to cause it to strike the bell, substantially as set forth.

4. The combination, with the sad-iron and its stock, of a bell suspended by its upper part from the stock, a thermostat upon the iron, and a hammer within and protected by the bell and liberated by the expansion of the thermostat, substantially as set forth.

Signed by me this 3d day of February, A. D. 1887.

GEO. J. MURDOCK.
